UNITED STATES PATENT OFFICE.

IRA J. OWEN AND BERNARD J. BOUWMEESTER, OF GRAND RAPIDS, MICHIGAN,
ASSIGNORS TO BISSELL CARPET SWEEPER CO., OF GRAND RAPIDS, MICHIGAN.

HANDLE.

1,309,775.

Specification of Letters Patent.

Patented July 15, 1919.

Application filed February 6, 1919. Serial No. 275,381.

To all whom it may concern:

Be it known that we, IRA J. OWEN and BERNARD J. BOUWMEESTER, citizens of the United States, residing at Grand Rapids, 5 county of Kent, State of Michigan, have invented certain new and useful Improvements in Handles, of which the following is a specification.

This invention relates to improvements in 10 handles.

Our improved handle is especially designed by us as a handle for carpet sweepers and suction cleaners and we have illustrated our improvements as embodied in a carpet 15 sweeper structure. Our improvements are, however, advantageous and readily adapted for use in various other relations.

The main object of this invention is to provide an improved handle, the parts of 20 which may be formed of rods and sheet metal stampings providing a light, but strong structure of graceful and attractive appearance.

Further objects, and objects relating to 25 structural details, will definitely appear from the detailed description to follow.

We accomplish the objects of our invention by the devices and means described in the following specification. The invention is 30 clearly defined and pointed out in the claims.

A structure which is a preferred embodiment of our invention is clearly illustrated in the accompanying drawing, forming a part of this specification, in which:

35 Figure I is a detail side view of a carpet sweeper embodying the features of our invention.

Fig. II is a detail plan view.

Fig. III is a detail view partially in section on a line corresponding to line 3—3 of 40 Fig. I.

Fig. IV is a detail view partially in section on a line corresponding to line 4—4 of Fig. II.

45 Fig. V is a section through the socket on a line corresponding to line 5—5 of Fig. II.

Fig. VI is a section through the shank on a line corresponding to line 6—6 of Fig. II, showing the manner of securing the socket 50 members thereto.

Fig. VII is an inside view of one of the socket members the other being a duplicate thereof.

Fig. VIII is a plan of the blank from

which the socket member of Fig. VII is 55 formed.

Fig. IX is a plan view of the blank from which the socket bushing is formed.

In the drawing similar reference characters refer to similar parts throughout the 60 several views, and the sectional views are taken looking in the direction of the little arrows at the ends of the section lines.

Referring to the drawing, 1 represents the body of a sweeper and 2 one of the wheels 65 thereof. These parts are shown in conventional form to illustrate an adaptation of our improvements.

The shank 3 of our improved handle is formed of a rod bent into a bail shape and 70 having the ends of its arms 4 turned inwardly at 5 to engage openings 6 in the sweeper body.

Washer-like collars 7 are arranged on the journal portions 5 and secured to the arms 75 4 by spot welding at 8.

Our improved socket comprises a pair of socket members 9 of semi-cylindrical cross-section each having a pair of semi-cylindrical laterally projecting arms 10 formed 80 integrally therewith. These socket members are duplicates and are arranged facing as shown in Fig. V and with their arms edge to edge and embracing the shank 3 as shown in Fig. IV. The socket members 85 are fixed or rigidly secured to the shank, preferably by means of spot welding, indicated at 11. The upper ends of the socket members are secured together and supported by a flanged ring 12 which is spun upon or 90 otherwise snugly fitted thereto.

To retain the handle proper 13 we provide a threaded bushing 14 formed of a piece of sheet metal 15 rolled into a cylinder and spirally corrugated to provide threads. 95 The lower end of the bushing is notched at 16 to engage the shank shown in Fig. IV, thereby preventing it from turning. Its upper end is engaged by the flanged ring 12 so that the bushing is securely retained and 100 100 constitutes a means for retaining the handle 13 and also a reinforcing member for the socket.

Our improved handle is light in weight and graceful and attractive in appearance 105 and also has the advantage of being economical and very strong.

We have illustrated and described our im-

provements as adapted to handles for carpet sweepers. We have not attempted to illustrate or describe other adaptations or embodiments as we believe the disclosure made will enable the adaptation thereof as may be desired.

Having thus described our invention, what we claim as new and desire to secure by Letters Patent, is:

- 10 1. In a handle, the combination of a bail-like shank, a pair of sheet metal socket members of semi-cylindrical cross section disposed edge to edge and each having a pair of laterally projecting semi-cylindrical arms at their lower end disposed edge to edge embracing said shank and spot welded thereto, a socket bushing formed of sheet metal rolled into a cylinder and spirally corrugated providing threads, said bushing 15 having notches in its lower end engaging said shank, and a flanged ring embracing the upper end of said socket members and overlapping the upper end of said bushing.
- 20 2. In a handle, the combination of a shank, a pair of complementary sheet metal socket members disposed edge to edge and having a pair of laterally projecting complementary arms disposed edge to edge embracing said shank and welded thereto, a

socket bushing formed of sheet metal rolled into a cylinder and notched to engage said shank, and a ring on the upper end of said socket members engaging said bushing.

3. In a handle, the combination of a shank, a pair of complementary socket members having laterally projecting complementary arms engaging said shank and fixed thereto, a threaded socket bushing engaging said shank, and a flanged ring embracing the upper end of said socket members and engaging the upper end of said bushing.

4. In a handle, the combination of a shank, a pair of complementary socket members having laterally projecting complementary arms engaging said shank and fixed thereto, a threaded socket bushing engaging said shank, and a ring embracing the upper end of said socket members.

In witness whereof, we have hereunto set to our hands and seals in the presence of two witnesses.
